UNITED STATES PATENT OFFICE.

FRANK D. URIE, OF ELGIN, ILLINOIS.

AUTOMATIC RECORDING SYSTEM FOR RADIO TIME-SIGNALS.

1,202,925.

Specification of Letters Patent. Patented Oct. 31, 1916.

Application filed December 19, 1914. Serial No. 878,102.

To all whom it may concern:

Be it known that I, FRANK D. URIE, a citizen of the United States, residing at Elgin, in the county of Kane, State of Illinois, have invented certain new and useful Improvements in Automatic Recording Systems for Radio Time-Signals, of which the following is a description, reference being had to the accompanying drawing and to the 10 figures of reference marked thereon.

My invention relates to the receiving, recording and comparing of radio signals, and has for its principal object the accurate comparison, by means of radio or wireless electric impulses, of time at a receiving or local 15 station with time at a sending or distant station.

In carrying my invention into effect I provide an organization of wireless receiving 20 apparatus and circuits, an intensifying system for the impulses received thereby, relays controlled by the intensified impulses, in combination with an electric chronograph upon which are registered for comparison 25 the record of the wireless impulses received from a distance, and local impulses originating at the local station where the receiving system is located.

As a practical illustration and application 30 of the invention it may be observed that certain standard clocks, such as at Washington, D. C., are equipped for sending radio impulses at intervals of one second, and in order to compare accurately with this standard clock the local clocks at various stations 35 it is necessary to provide measurements down to very small fractions of a second. This is accomplished by the practice of my invention, which therefore consists in the 40 combination and arrangement of apparatus and circuits hereinafter described and claimed, and illustrated in the accompanying drawings, in which—

Figure 1 is a diagrammatic view of a sending station from which the standard time impulses are sent out; no specific impulse generating means being shown; Fig. 2 is a diagrammatic view of the apparatus and circuits at the local or receiving station; and 45 Fig. 2^a is a diagram of the apparatus and

circuits for generating the local time electrical impulses at the local station.

Referring to the drawings the aerial or antenna at the sending station is indicated at A, this being connected directly or indirectly to ground at G. 55

C is a diagrammatic indication of a standard clock for controlling the sending of periodic standard time radio impulses, the means shown being contacts c co-operating 60 with a moving part of the clock, such as the pendulum, for the purpose of generating impulses at intervals of one second. Any suitable wave generating apparatus and circuits may be used at the sending station, and it is 65 therefore considered unnecessary to complicate the drawing by showing this portion of the equipment of the sending station.

At the receiving or local station the radio impulses are received through the aerial or 70 antenna A¹ connected to ground G¹ through variable condenser K in parallel with primary of the transformer I. The impulses or oscillations are communicated through transformer I, of which i¹ and i² are the primary 75 and secondary windings respectively, to the receiving circuit which includes a crystal detector D or other device sensitive to the electrical oscillations. Variable condenser K¹ is bridged across this circuit, as is also condenser K². This is one of the standard types 80 of receiving circuits and apparatus, and it will be understood that other forms of detectors and receivers may be employed in place of those shown. 85

In order to intensify or amplify the impulses or currents in the detector circuit I provide a set of audion detectors, as shown in the drawing. These detectors are well known to those skilled in the art, so that a 90 detailed description thereof is deemed unnecessary, but a brief description may be desirable for the proper understanding of my invention. Each of the detectors comprises a filament F mounted within an 95 evacuated container, a plate P which may be of platinum or other suitable material, and a grid g. One side of the detector circuit is connected by conductor 1 with grid g of the first audion detector D¹, and the other side 100

of the detector circuit is connected by conductor 2 with one terminal of filament F. The other terminal of filament F is connected by conductor 3 with one terminal of 5 a small battery b, the other terminal of said battery being connected through rheostat R¹ with the first mentioned terminal of filament F. Conductor 3 also connects with one terminal of battery B, the other terminal 10 of which is connected through the adjusting switch b¹ and self-induction coil I¹ with plate P.

The other audion detectors D², D³, and D⁴, are similarly constructed, one terminal of 15 the filament of the second detector D² being connected by conductor 4 with the amplified portion of the circuit of detector D¹, and the grid of detector D² being connected to the other side of said amplified portion, including 20 between said connections the self-induction coil I¹. The remaining audion detectors, with their respective batteries and rheostats are similarly connected with the exception of the last, the terminals of which 25 are connected to sensitive relay r. As this and the other relays herein mentioned are well known constructions detailed description thereof is deemed unnecessary, but it will be observed that all of the relay 30 circuits are break circuits. As relay r is too delicate to control a circuit including a strong source of current, I connect to its controlled circuit a second relay, which may be termed a pony relay r¹, in the circuit of 35 which is included a battery and a regulating rheostat, a condenser being bridged across this circuit. Relay r¹ controls the circuit of electro-magnet E of an electric chronograph the record cylinder of which is indicated at 40 e and the clock mechanism at e¹. The circuit of electro-magnet E includes an adjusting rheostat, and a battery having sufficient strength to operate the armature e² of the magnet which controls the stylus of 45 the chronograph. These parts are shown diagrammatically as this apparatus is well known in the art.

In order to compare the intervals of the time at the local or receiving station with 50 those indicated by wireless emanations from the standard transmitting station, I provide the local clock C¹ with means for making and breaking a local circuit at pre-determined intervals. If the impulses so 55 generated were permitted to act directly upon the chronograph there would be a discrepancy in the comparison with the intervals of the standard clock, owing to the time lag of the wireless receiving apparatus and relays employed for operating the chronograph. I therefore utilize means 60 at the receiving station for generating radio impulses corresponding to the time intervals of the local clock, these local radio impulses

being capable of affecting the radio receiving apparatus at the local station. This is accomplished by providing contacts H which are controlled by electro-magnet h in the circuit which is made and broken by the local clock C¹, the circuit which includes 70 these contacts H also including a battery h¹ of sufficient strength to produce a spark which will give rise to the desired radio impulses. This circuit may also include other apparatus such as a sounder J which 75 may be located at any desired point in the station. It will thus be seen that the time lag of the apparatus at the receiving station, being common to the standard clock impulses and the local clock impulses, may be 80 disregarded.

It will be understood that the various apparatus and parts thereof are shown merely diagrammatically and that in practice the proper arrangement and proportioning of 85 the parts is readily effected. It will also be understood that suitable precautions will be taken to prevent certain parts of the apparatus from interfering with the operation of other parts. For instance, if the breaking of any of the relay or electro-magnet circuits should result in sparks which interfere with the operation of the wave generating contacts H they will be provided with suitable screens to prevent the radiation of the 90 interfering impulses.

The operation of the system may be briefly described as follows: It may be assumed that the standard clock C at the sending station is arranged to send radio impulses at intervals of one second, and that the local clock C¹ at the local or receiving station, the intervals of which are to be compared with those of the standard clock, is similarly arranged to cause the generation of radio impulses at 100 contacts H. Both of these sets of impulses will affect the detector D of the receiving station and the impulses thereby caused in the receiving circuit will be amplified or intensified by the successive action of the audion detectors and their associated batteries and circuits. Of course the number of these audion detectors is optional, and a greater or less number than those shown may be employed if desired. The impulses so 105 amplified are then capable of affecting the delicate relay r which in turn controls the circuit of relay r¹ which in its turn controls the circuit of electro-magnet E. It may be assumed that the record drum e of the 110 chronograph revolves once a minute, and a record will therefore be produced of both sets of radio impulses, one impulse in each 115 set occurring each second. By measuring the records so produced the differences, if any, between the beats of the local clock and the standard clock may be determined within a very small fraction of a second.

In addition to the above described use of the system, the system may also be employed for recording regular wireless telegraphic messages by dots and dashes or any other 5 code system, and it has already been successfully so employed at great distances. It will be understood, therefore, that I am not limited to the particular application of the invention described. The apparatus 10 described or any portion thereof may be used for other purposes without departing from the spirit of the invention as set forth in the appended claims.

Having thus described my invention, what 15 I claim as new and desire to secure by Letters Patent, is:

1. In a system for comparing time at a receiving station with time at a sending station, the combination with a sending station 20 having means for generating periodic time radio impulses, of a receiving station having receiving means for said impulses, means for intensifying the received impulses, means for generating time periodic electrical 25 impulses at the receiving station, and a device for recording said sets of impulses for relative comparison.
2. In a system for comparing time at a receiving station with time at a sending station, the combination with a sending station 30 having means for generating periodic time radio impulses, of a receiving station having receiving means for said impulses, means for intensifying the received impulses, means for 35 generating periodic time electric impulses at the receiving station, a relay controlled by said intensified impulses, a local circuit controlled by said relay, and an electric chronograph operated by said local circuit and said periodic time impulses generated at the receiving station.
3. In a system for comparing time at a receiving station with time at a sending station, the combination with a sending station 40 having means for generating periodic time radio impulses, a receiving station having receiving means for said impulses, a series of audion detector intensifiers for said received impulses, means for generating periodic time electric impulses at the receiving station, and a device for recording said sets of impulses for relative comparison.
4. In a system for comparing time at a receiving station with time at a sending station, the combination with a sending station 45 having means for generating periodic time radio impulses, a receiving station having receiving means for said impulses, a series of audion detector intensifiers for said received impulses, means for generating periodic time 50 electric impulses at the receiving station, a relay controlled by said intensified impulses, a local circuit controlled by said relay, and an electric chronograph operated by said local circuit and said local periodic time impulses generated at the receiving station.
5. In a system for comparing time at a receiving station with time at a sending station, the combination with a sending station 55 having means for generating periodic time radio impulses, a receiving station having receiving means for said impulses, a series of audion detector intensifiers for said received impulses, means for generating periodic time 60 electric impulses at the receiving station, a relay controlled by said intensified impulses, a local circuit controlled by said relay, and an electric chronograph operated by said local circuit and said periodic time impulses generated at the receiving station.
6. In a system for comparing time at a receiving station with time at a sending station, the combination with a sending station 65 having means for generating periodic time radio impulses, of a receiving station having receiving means, means for intensifying the received impulses, means for generating periodic time radio impulses at the receiving station capable of affecting said receiver, and a device for recording both sets of impulses for relative comparison.

by said local circuit and said periodic time 65 impulses generated at the receiving station.

5. In a system for comparing time at a receiving station with time at a sending station, the combination with a sending station 70 having means for generating periodic time radio impulses, of a receiving station having receiving means, means for intensifying the received impulses, means for generating periodic time radio impulses at the receiving station capable of affecting said 75 receiver, and a device for recording both sets of impulses for relative comparison.

6. In a system for comparing time at a receiving station with time at a sending station, the combination with a sending station 80 having means for generating periodic time radio impulses, of a receiving station having receiving means for intensifying the received impulses, means for generating periodic time radio impulses at the receiving station capable of affecting said receiver, a relay controlled by said intensified impulses, a local circuit controlled by said relay, and an electric chronograph operated by said local circuit and said periodic time 85 impulses generated at the receiving station.

7. In a system for comparing time at a receiving station with time at a sending station, the combination with a sending station 90 having means for generating periodic time radio impulses, of a receiving station having receiving means, a series of audion detector intensifiers for said received impulses, means for generating periodic time electric impulses at the receiving station, 100 and a device for recording said sets of impulses for relative comparison.

8. In a system for comparing time at a receiving station with time at a sending station, the combination with a sending station 105 having means for generating periodic time radio impulses, of a receiving station having receiving means, a series of audion detector intensifiers for said received impulses, means for generating periodic time 110 electric impulses at the receiving station, a relay controlled by said intensified impulses, a local circuit controlled by said relay, and an electric chronograph operated by said local circuit and said local periodic time 115 impulses generated at the receiving station.

9. A receiving device having means for receiving radio time signals from a distant station, means for intensifying the received impulses, means for generating in proximity 120 to said receiving means periodic time radio impulses capable of affecting said receiving means, and a device for recording said impulses for comparison.

10. A receiving station having radio time 125 signal receiving means, means for intensifying the received signal impulses, a local clock at the receiving station, a circuit

4
periodically opened and closed by said clock, an electro-magnet operated through said circuit, a circuit at the receiving station including a source of current and contacts controlled by said electro-magnet to produce radio impulses capable of affecting said receiver, and a device for recording for relative comparison said impulses together with

other impulses from a distant station affecting said receiving means.

In testimony whereof, I affix my signature in the presence of two witnesses.
